US00D947855S

(12) **United States Design Patent** (10) **Patent No.:** **US D947,855 S**
(45) **Date of Patent:** **** Apr. 5, 2022**

(54) **COVER**

(71) Applicant: **Apple Inc.**, Cupertino, CA (US)

(72) Inventors: **Jody Akana**, San Francisco, CA (US); **Molly Anderson**, San Francisco, CA (US); **Bartley K. Andre**, Palo Alto, CA (US); **Shota Aoyagi**, San Francisco, CA (US); **Anthony Michael Ashcroft**, San Francisco, CA (US); **Marine C. Bataille**, San Francisco, CA (US); **Jeremy Bataillou**, San Francisco, CA (US); **Markus Diebel**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Julian Jaede**, San Francisco, CA (US); **Duncan Robert Kerr**, San Francisco, CA (US); **Peter Russell-Clarke**, San Francisco, CA (US); **Benjamin Andrew Shaffer**, San Jose, CA (US); **Mikael Silvanto**, San Francisco, CA (US); **Sung-Ho Tan**, San Francisco, CA (US); **Clement Tissandier**, San Francisco, CA (US); **Eugene Antony Whang**, San Francisco, CA (US); **Rico Zörkendörfer**, San Francisco, CA (US)

(73) Assignee: **Apple Inc.**, Cupertino, CA (US)

(**) Term: **15 Years**

(21) Appl. No.: **29/656,622**

(22) Filed: **Jul. 13, 2018**

(51) LOC (13) Cl. **14-02**

(52) U.S. Cl.

USPC **D14/444**

(58) **Field of Classification Search**

USPC D14/203.4, 203.6, 250-251, 315-327,

CLAIM

The ornamental design for a cover, as shown and described.

DESCRIPTION

FIG. 1 is a bottom front perspective view of a cover showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a side view of the cover of FIGS. 1-7 in an alternate configuration and in an environment of use;

FIG. 9 is another side view thereof in a second alternate configuration and in an environment of use;

FIG. 10 is another side view thereof in a third alternate configuration and in an environment of use;

FIG. 11 is a bottom front perspective view of a second embodiment of a cover showing the claimed design;

FIG. 12 is a front view thereof;

FIG. 13 is a rear view thereof;

FIG. 14 is a left side view thereof;

FIG. 15 is a right side view thereof;

FIG. 16 is a top view thereof;

FIG. 17 is a bottom view thereof;

FIG. 18 is a side view of the cover of FIGS. 11-17 in an alternate configuration and in an environment of use;

FIG. 19 is another side view thereof in a second alternate configuration and in an environment of use; and,

FIG. 20 is another side view thereof in a third alternate configuration and in an environment of use.

The broken lines in the figures show environment that forms no part of the claimed design.
